ROCKING LOUNGE CHAIR

Daniel F. Caldemeyer, Vanderburgh County, Ind. (4300 Jennings Lane, Evansville, Ind. 47712), and Lloyd O. Caldemeyer, 3815 E. Mulberry St., Evansville, Ind. 47715

Filed Dec. 30, 1965, Ser. No. 386

Term of patent 14 years

(Cl. D15—6)

FIG. 1 is a view in side elevation of a rocking lounge chair showing our design;

FIG. 2 is a view in front elevation of the new and novel design of FIG. 1;

FIG. 3 is a top plan view of the applicants' new and novel rocking lounge chair design; and,

FIG. 4 is a view in rear elevation of the novel design invention of FIGS. 1 to 3, inclusive.

The side of the chair not shown is a mirror image of the side shown except for the control lever.

We claim:

The ornamental design for a rocking lounge chair, as shown and described.
